DIETWALD THIERBACH, OF CHARLOTTENBURG, BERLIN, GERMANY, ASSIGNOR TO SIEMENS & HALSKE AKTIENGESELLSCHAFT, OF SIEMENSSTADT, NEAR BERLIN, GERMANY, A COMPANY OF GERMANY

MEASUREMENT OF ECHO EFFECTS IN TRANSMISSION SYSTEMS

Application filed March 11, 1927, Serial No. 174,539, and in Germany April 27, 1926.

The invention relates to a method which enables the echo-effects occurring in long telephone connections to be measured. As is known, echoes may occur in a telephone communication system, for instance, in a four-wire transmission system, because a part of the incoming speech currents passes into the return line owing to inaccurate line simulation at the branching points and thus the speech currents become again audible at the calling station.

According to this invention the measurement of echo-effects consists in comparing the echo currents or echo voltages returning to the calling station with the outgoing original currents or voltages. The invention is based on the fact that a line in which an echo-effect occurs may be replaced with respect to the calling station by an active bi-polar device, for instance, by an impedance of the magnitude of the impedance of the outgoing line in series with the E. M. F. of the echo.

Fig. 1 shows, by way of example, the calling station, represented by a microphone M in series with the microphone battery B, which produces an initial voltage V_a at the input end of the line to be tested. With respect to the voltages and currents present at the input of the line, the connection is replaced by an impedance Z in series with the E. M. F. of the echo V_e . Here V_e is always proportional to the impressed voltage V_a ; approximately $V_e = k \times V_a$, where k can be conveniently called the echo-factor. When the echo disappears, for example, when one of the return wires of a four-wire connection is broken, the input impedance of the line $Z_1 = Z$, where as when the return line is effective

$$Z_2 = \frac{Z}{1+k}$$

Thus the echo-factor k can be determined, for example, by measuring the impedance Z_1 of the outgoing line when the return line is

broken, and the impedance Z_2 when it is effective. From these two measurements the echo-factor may be determined by the equation

$$k = \frac{Z_1 - Z_2}{Z_2} . \quad 50$$

It is advisable to call the natural logarithm of k the echo-attenuation in conformity with the nomenclature which is usual in the telephone art. This echo attenuation can be determined according to the present invention for example with the aid of a device which consists essentially of an impedance measuring bridge. From the measured values Z_1 and Z_2 the echo-attenuation is given by

$$b = \log_e \left(\frac{Z_1 - Z_2}{Z_2} \right)$$

Fig. 2 shows as an example a further measuring device for determining the echo; this also being based upon the fact that a line with an echo can be replaced by a circuit in which an originating source and an echo source are present.

The arrangement consists substantially of a bridge comprising resistances R_1, R_2, R_3, R_4 . The voltage of source S tapped off at the bridge arm R_1 acts through a resistance R , which should be approximately equal to Z , and is impressed on the input of the line which is to be investigated. R_1 is a resistance which is small with respect to Z or R and the portion of the voltage tapped off at R_1 , acting upon the line, is the voltage drop across R , since the voltage drop across R is equal to the voltage drop across Z , R and Z being equal as stated. Under these conditions, if the echo voltage V_e is zero, the bridge is balanced and the telephone T_1 gives zero response. In this case the voltage across R_4 is equal to the voltage V_a passing into the line. If, however, there is an echo voltage V_e active, the telephone T_1 gives a response which is proportional to the echo voltage.

Preferably the resistance of the telephone or other indicating instrument is made great with respect to the resistance R . The voltage impressed on the telephone T_1 is then for all practical purposes given by $V_1 = V_e/2$. Then the indication given at T_1 is compared with the indication arising at T_2 . For this purpose R_4 is preferably designed as a potentiometer. If, for example, the m th portion of the voltage V_a prevailing at R_4 is tapped off for T_2 ,

then the voltage at T_2 is given by $V_2 = \frac{1}{m} \times V_a$.

If the two telephones give the same sound, then $V_1 = V_2$ or $V_e = \frac{2}{m} \times V_a$. From this the echo-factor or the echo-attenuation can be calculated from the known dividing ratio m . It is within the scope of the invention to employ any other suitable indicating means to determine when the voltages across T_1 and T_2 are equal.

What is claimed is:

1. In an echo intensity measuring circuit, a bridge circuit therefor, a source of potential supplied through said bridge circuit to a line to be tested, and means included in said bridge circuit for determining the ratio of the potential impressed on the line to the echo potential.
2. In an echo intensity measuring circuit, a bridge circuit for supplying a potential to the line to be tested, said bridge circuit including a potentiometer for comparing the echo potentials to the impressed potentials, said potentiometer determining the ratio of the echo potentials to the impressed potentials.
3. In an echo intensity measuring circuit, a Wheatstone bridge arrangement including a potentiometer, a source of alternating current to be impressed on a test line through said bridge, an indicating device across said bridge balanced with respect to said source, said indicating device being responsive to potentials in said test line, another indicating device whose response is to be compared with that of said first indicating device, said other indicating device being responsive to potentials arising at said source, and derived from said potentiometer in which currents from said source are not balanced out.

In witness whereof, I hereunto subscribe my name this 21st day of February, A. D. 1927.

DIETWALD THIERBACH.
